UNITED STATES PATENT OFFICE

WILSON L. WITHROW, OF PUYALLUP, WASHINGTON

INCANDESCENT BULB ATTACHMENT

Application filed December 23, 1930. Serial No. 504,358.

This invention relates to an improved attachment for an incandescent bulb, particularly the type of bulb which is used in present-day motor vehicle headlights.

It is a matter of common knowledge that the rays of light projected from the upper half and forward portion of the bulb in a headlight construction are generally projected forwardly unreflected.

I am aware of the fact that many different kinds of reflectors, lenses, and bulbs have been employed with a view toward eliminating objectional glare headlight beam projection. With certain known prior art devices in mind, I have evolved and produced a simple and expedient device in the nature of an economical attachment susceptible of application to a conventional light bulb, the attachment being characterized by appropriate attaching means, and an especially designed segmental shield or blind which cooperates with the upper frontal portion of the bulb in such a manner as to intercept the light rays which emanate from this portion of the bulb.

The specific features which serve to characterize and add to the novelty of this practical contribution to the art will become more readily apparent from the following description and drawings.

In the drawings:

Figure 1 is a side elevational view of an ordinary light bulb showing the attachment in position.

Figure 2 is a cross section on the line 2—2 of Figure 1 and through the attachment per se.

Figure 3 is a bottom plan view of the structure shown assembled in Figure 1.

Figure 4 is a section on the line 4—4 of Figure 1.

Figure 5 is a perspective view of the attachment by itself.

In the drawings, in Figure 1, the bulb is generally denoted by the numeral 6, while the numeral 7 designates the metallic mounting or extension thereof adapted for removable reception in a customary light socket.

The attachment is generally designated by the numeral 8. As seen in Figure 5, this at-

55 attachment comprises a metallic portion including a central plate-like part 9 constituting a shield. This is of predetermined proportions and shape, being preferably shaped as shown in the drawings.

Attached to and extending rearwardly from this plate-like portion are spaced parallel flexible attaching arms or straps 10 and 11. The straps 10 terminates at its inner end with a curvate retaining clip 12. A similar reversely curved companion clip 13 is formed on the corresponding end of the arm 11. These two clips come together to embrace the part 7 of the bulb. Then a knurled retaining collar or ring 14 is slipped over 65 these fingers or clips to hold them in place and to also hold the complete attachment in operative position.

A predominating feature of the invention is founded upon the use of an asbestos pad 15 which is of a shape corresponding to the shield 9 and which is held in place by the laterally bent retaining fingers 16. Not only does this element 15 serve as a pad to afford a cushioning surface for the shield, but it 70 constitutes a practical heat insulating means and further serves as a spacer for holding the longitudinally bowed arms 10 and 11 in spaced relation to the globe or glass bulb 6.

The gist of the invention is in the provision 75 of a segmental suitably curved shield which conforms to and is disposed against the upper frontal portion of the bulb 6, together with retaining arms, preferably arranged at diametrically opposite points and so fashioned at their inner ends to permit them to be releasably mounted on the part 7 to form a retaining frame for the shield.

A paramount feature of the improvement 80 however, is the utilization of the asbestos pad 15 which is desirable because of its cushioning and insulation properties.

When in place, the attachment will materially lessen objectionable light rays by intercepting the rays which would ordinarily pass 85 through the upper frontal portion of the bulb.

This device eliminates all glare that blinds oncoming traffic and also prevents the illumination of the particles of the atmosphere which reflects back into the eyes of the driver 100

forming a light screen which obstructs the view of the road.

This device when properly installed in a headlamp that is correctly positioned, focused and aimed prevents glare and permits 5 a better vision at all times.

It is thought that the description, taken in connection with the drawings, will enable a clear understanding of the invention to be had. Therefore, a more lengthy description 10 is thought unnecessary.

While the preferred embodiment of the invention has been shown and described, it is to be understood that minor changes coming 15 within the field of invention claimed may be resorted to if desired.

I claim:

A light bulb shield of the class described comprising a plate of substantially semi-circular shape and curved to fit a part of the 20 large end of the bulb, arms formed with the plate at the corners thereof, curved laterally extending arms on the free ends of the first mentioned arms curving in opposite directions to encircle the base of the bulb, a ring 25 for encircling the laterally extending arms for holding the lateral arms in position on the bulb, a sheet of heat resisting material of the same shape as the plate and placed on the 30 inner face thereof, and tongues on said plate bent over the sheet to hold the same in place.

In testimony whereof I affix my signature.

WILSON L. WITHROW.
